DOOR CLOSER AND CHECK.

No. 833,387.

Specification of Letters Patent.

Patented Oct. 13, 1906.

Application filed September 1, 1905. Serial No. 978,689.

To all whom it may concern:

Be it known that I, WILLIAM K. HENRY, a citizen of the United States, residing at New Britain, county of Hartford, Connecticut, 5 have invented certain new and useful Improvements in Door Closers and Checks, of which the following is a full, clear, and exact description.

My invention relates to closers and checks 10 for doors, and particularly such as are located in the floor or door-sill, which serve also to support the door.

The object of the invention is to provide a 15 check of simple construction which may be economically manufactured, readily assembled or taken apart for repairs or replacement, and which is efficient and quick acting and will permit of a wide angle of swing of the door. I have also sought to prevent twisting or wearing of the parts, which has previously made this general type of check in some instances objectionable.

These objects are accomplished in the manner hereinafter described by a construction 25 which will be more clearly understood from an inspection of the accompanying two sheets of drawings.

Briefly, it may be said to comprise a casing having separate chambers for the checking 30 and closing mechanism, together with a two-part spindle provided with a support intermediate its length and packing for the checking chamber or cylinder, together with a special form of spring and slide for coacting 35 with eccentrically-disposed rollers on the spindle to bring the parts into position when the door is closed or permit a wide swing of the door. The by-pass for controlling the checking fluid is readily accessible from one 40 side of the casing and affords a delicate means of adjustment. By reason of the structure of the spindle-rollers and slide and the relative arrangement thereof the door is provided with slight resistance in the beginning 45 of the opening movement, and a much greater impulse is given when the door begins to close.

Figure 1 is a longitudinal section and elevation of a sill closer and check embodying 50 the improvements of my invention. Fig. 2

is a view of the spindle and a packing-gland, the lower half of said spindle and gland being in section. Fig. 3 is a fragmentary vertical cross-section on the plane of the by-pass 26, Fig. 5, showing the location and construction 55 of the by-pass control and the guide for the closer-slide. Fig. 4 is a detail plan view of the lower half of the spindle. Fig. 5 is a plan view of the entire mechanism, but with the cover-plate removed.

1 is the casing, having two separate chambers 2 and 3 for the closing and checking mechanism, respectively. The chamber for the closing mechanism extends horizontally considerably beyond the chamber for the 65 checking mechanism. By this arrangement it is possible to construct a powerful mechanism and condense it into such a space that it may be placed beneath a door-sill without requiring so large a cut-out as is necessary 70 for structures of the prior art.

4 is a gland removably secured in the casing, preferably by a screw-thread.

5 is the lower part of the spindle, which is 75 rotatively mounted in the bottom of the casing and has also a bearing in the gland 4.

6 is the checking-piston, connected by rod 8 to the crank-arm 7, which is fast on part 5 of the spindle.

9 is a ring threaded in the gland 4 for 80 clamping the packing around the upper end of the spindle part 5 and preventing the checking fluid from leaking from its chamber 3.

10 is the upper part of the spindle, which is 85 removably mounted in the lower part 5, but constructed to removably engage and rotate the same.

11 is a shoe having a recess and adapted to be secured in the lower edge of the door for 90 affording a seat therefor upon the upper end of the part 10 of the spindle.

12 is a cover for the casing, removably secured in place and also providing a bearing for the upper end of the spindle part 10.

13 is a peculiarly-formed spring spirally 95 coiled, so as to have a much greater width than height. This permits of the use of a powerful spring without requiring great depth in the casing, the width being of relatively small consequence.

14 is a block guided between the shoulders 15 and 16 in the casing and normally under compression of the spring 13.

17 is an offset portion of the spindle part 5 10, carrying rollers 18 and 19, which bear against the cam-surfaces 20 and 21, formed in the block 14. These rollers 18 and 19 are both mounted back of the axis of the spindle 10, and their radius of operation is such relative to the cam-surfaces 20 and 21 that they cause a small movement of the slide 14, and consequently a slight compression of the spring 13 when the door begins to open, which movement increases in rapidity as the door is opened, and vice versa.

The checking fluid—for instance, oil—is filled into the chamber 3, preferably before the casing is placed in the floor or sill, and then the cover 22 secured tightly in place. A 20 passage through the piston is controlled by a check-valve 23. In the wall of the cylinder is an escape-passage 24, which allows a small quantity of the checking fluid to pass by the piston. A by-pass is also provided, leading 25 from one end of the cylinder around the piston to the other end of the cylinder. This by-pass consists of the two parts or branches 25 and 26, connected to the chamber 27 at one side of the casing. This by-pass is not 30 closed by the action of the piston.

28 is a controllable valve for regulating that part of the checking fluid which passes through the by-pass 25 and 26 by partially closing one or both passages 25 or 26 thereof.

35 29 is a gland around the valve for forcing the packing 30 into place around the same.

The opening movement of the door causes the spindle to rotate, and one of the rollers bears against the sliding block 14, thus moving 40 the block to the left and compressing the spring. At the same time the crank-arm 7, which is fast on the spindle and pivotally connected to the piston-rod 8, causes the piston to be moved to the right. When the

45 door is released, the spring, acting through the medium of block 14 and one of the rollers carried by the spindle, causes a reverse rotation of the spindle, tending to close the door and moving the piston to the left. This 50 movement of the piston puts the checking liquid under compression, which acts to seat the valve, so that the liquid is permitted to gradually escape through the restricted opening and the by-pass 25 26, whereby the closing movement of the door is checked to permit it to gradually return to its closed position.

The spindle being formed in two 55 parts permits of the use of the intermediate bearing, so that eccentricity of movement of the spindle is prevented. The parts can 60 also be more conveniently assembled and taken out for repair.

The advantages of the invention will be apparent to those who are skilled in this art. What I claim is—

65

1. In a check and closer, a vertical spindle formed in two parts separably connected together, closing mechanism coacting with one part and checking mechanism coacting with the other part.

70 2. In a check and closer, a casing having two chambers one above the other, a spindle passing through both chambers and stepped in the bottom of the casing, a horizontally-acting coiled closing-spring and means of connection with the spindle in the upper chamber, and checking mechanism in the lower chamber connected to the spindle.

75 3. In a door-check, a casing having a checking-chamber and a by-pass 25 26 with a control-chamber 27, means for controlling the flow of liquid through said control-chamber, a spindle supported in said casing, a piston reciprocable in said checking-chamber and operatively connected to said spindle and 80 having a passage for checking liquid, and a check-valve carried by the piston in said passage.

85 4. In a door closer and check, a casing, a spindle formed in two separable parts, one seated in the other, and three bearings for said spindle, one at the top, one at the bottom, and the other intermediate the top and bottom, closing means coacting with one part of the spindle, and checking means coacting with the other part of the spindle.

90 5. In a door-check, a vertical spindle formed in two parts, one of said parts having an axially-arranged recess and the other part removably fitting therein.

95 6. In a door-check, the combination of a two-part casing, a gland between the parts, a lower spindle part stepped in said casing having a bearing in said gland, and a second spindle part removable from said first-mentioned spindle part.

100 7. In a door closer and check, a casing having two chambers, a spindle passing through said chambers, longitudinally-acting closing mechanism arranged in the upper chamber, a cover for said chamber and mechanism, checking mechanism arranged in the lower chamber, and a removable end cap for said chamber.

105 8. In a door closer and check, a casing formed with two chambers, a spindle passing therethrough and stepped in the lower part of the casing, checking mechanism connected to the lower part of the spindle, a gland forming a bearing for the intermediate portion of said spindle, longitudinally-acting closing mechanism in the upper chamber of said casing, and a cover for said chamber affording a bearing for the upper part of said spindle.

9. A door check and closer comprising a casing having two chambers one above extending longitudinally beyond the other, a spindle mounted in said casing, formed in two separable parts, closing mechanism arranged in the upper chamber and coacting with the upper part of the spindle and check-
ing mechanism arranged in the lower chamber and coacting with the lower part of the spindle.
